UNITED STATES PATENT OFFICE.

WILHELM BORGmann, OF DÜSSELDORF, GERMANY.

SIGN.

No. 834,447.

Specification of Letters Patent.

Patented Oct. 30, 1906.

Application filed March 23, 1906. Serial No. 307,661.

To all whom it may concern:

Be it known that I, WILHELM BORGmann, a citizen of Germany, residing at Düsseldorf, Germany, have invented new and useful Improvements in Signs, of which the following is a specification.

This invention relates to a sign having characters which may be readily removed and replaced without displacing or interfering with the adjoining characters.

The sign may be used as a station-indicator for restaurants and for other purposes.

In the accompanying drawings, Figure 1 is a front view, partly broken away, of part of a sign embodying my invention; Fig. 2, a cross-section thereof, showing the characters in position; and Fig. 3, a similar section showing one of the characters partly withdrawn.

The back plate *c* of the sign is provided with a suitable number of parallel rails *d*. Each of these rails has an upper groove *a* and a lower groove *b*, the former being deeper than the latter. The tablets *e*, bearing the letters or characters *f* to be displayed, are of a height less than the distance between the webs of two adjoining rails *d*. Thus by

slightly lifting a tablet through a suction-cup *g* or otherwise, Fig. 3, its lower edge may be raised above lower rail *d*, so that the tablet may be readily tilted forward prior to its removal. To prevent tampering, the upper groove *a* contains above tablet *e* a key *s*, composed of a strip of wood, a string, or similar device extending along the entire length of the sign. This key may be locked to the sign-board in suitable manner and must be withdrawn before the tablet can be tilted.

What I claim is—

A sign provided with an upper rail having a groove, a lower rail having a groove of less depth than that of the upper rail, a tablet removably engaging the rails and shorter than the distance between the rail-webs, and a removable key between the tablet and the upper rail, substantially as specified.

Signed by me at Düsseldorf, Germany, this 3d day of March, 1906.

WILHELM BORGmann.
